UNITED STATES PATENT OFFICE.

HENRY F. HAGER, OF CHICAGO, ILLINOIS, ASSIGNOR TO HENRY SCHOMER COMPANY, OF CHICAGO, ILLINOIS, A CORPORATION OF ILLINOIS.

METAL FABRIC.

1,191,693.

Specification of Letters Patent. Patented July 18, 1916.

Application filed November 9, 1914. Serial No. 870,992.

To all whom it may concern:

Be it known that I, HENRY F. HAGER, citizen of the United States, residing at Chicago, in the county of Cook and State of Illinois, have invented a certain new and useful Improvement in Metal Fabric, of which the following is a full, clear, concise, and exact description, reference being had to the accompanying drawings, forming a part of this specification.

My invention relates to metal fabrics and finds a very useful embodiment in bed mattress supporting fabrics, though the invention is not to be limited to such use.

13 The fabric of my invention comprises a plurality of substantially parallel load supporting members in combination with links disposed transversely to said members and provided with member engaging formations 20 that operate to limit the extent to which adjacent load supporting members may be spread apart, whereby the fabric is limited to a predetermined maximum width, said link formations, however, permitting the 25 mutual approach of adjacent load supporting members, and preferably the mutual approach of any two load supporting members whether adjacent or not.

In the preferred embodiment of the invention the load supporting members are in 30 the form of normally parallel longitudinally disposed thin metallic strips constituting slats, while the transverse links are composed of similar material. Each link is 35 preferably in coupling relation to but two, and adjacent, slats and the links in adjacent longitudinal rows thereof are preferably staggered the more effectively to permit the mutual approach of any two slats. Each of 40 these short links preferably terminates in hooks whose entrance openings face each other to permit of the mutual approach of the slats they couple and to define a limit within which these slats may spread where 45 coupled.

I will explain my invention more fully by reference to the accompanying drawing showing the preferred embodiment thereof and in which—

50 Figure 1 is a plan view illustrating the formation of my fabric; Fig. 2 is a sectional view on line 2 2 of Fig. 1; Fig. 3 illustrates the formation of a part of a slat; and Fig. 4 is a bottom view of the formation illustrated in Fig. 3.

Like parts are indicated by similar characters of reference in the different figures.

A rectangular frame *a* has attached to two of its opposite sides the coil springs *b* whose inner ends are connected with slats of strip *c*. These slats are slit at intervals, portions of the slats margining the slits being removed—depressed—from the plane of the slats as indicated at *d*. Thus the portions margining each slit are vertically 60 spread apart to form an opening of sufficient height in which the link there received may move transversely with respect to the engaging slat, the depressed portions of the slats being sufficiently removed from the 65 plane of the slats to afford spacing *e* that is sufficient to receive the strip metal links *f* while these strip metal links are in a plane parallel with the plane of the slats, the ends of the strip metal links being inturned to 70 form hooks which normally receive the depressed portions of the slats. The links are distributed in longitudinal rows, each row being disposed between adjacent slats, the links in one row being staggered with respect to the links in the next row. Each link, where it engages a slat, passes over the 75 top surface of the adjacent depressed portion of the slat and passes under the bottom surface of the undepressed adjacent portion 80 of the slat, these two slat surfaces operating so to guide the link in its motion with respect to the contiguous slat as always to maintain the depressed portion of the slat and the hook space at the adjacent end of the 85 link in the same plane whereby no degree of relative lateral movement between the slats of the fabric will be sufficient to uncouple the slats and links. Thus the engagement between the slats and links is such that the 90 slats and links coöperate to insure reengagement between the hook ends of the links and the depressed portions of the slats whenever the depressed portions of the slats are removed from engagement with the hook 95 ends of the links. The outside slats *c* are desirably heavier than the remaining slats, and in order to prevent the outer links from projecting laterally of the fabric beyond the slats *c* the outer ends of the links of each 100 outer longitudinal row of links are riveted to said outside slats. Further to increase the marginal strength of the fabric each end of each outside slat *c* is coupled with the fabric supporting frame by two springs 105

110

b. Not only may various slats be permitted mutual approach independently of other slats, but any two slats may be more nearly approached at either end of the fabric than at the other, as will be apparent by an inspection of the drawing.

While I have herein shown and particularly described the preferred embodiment of my invention I do not wish to be limited 10 to the precise details of construction shown as changes may readily be made without departing from the spirit of my invention, but

Having thus described my invention I claim as new and desire to secure by Letters 15 Patent the following:—

1. A metallic fabric including a plurality of slats placed side by side and formed of strip metal and rows of links formed of strip metal each row being disposed between 20 adjacent slats, the links being staggered in adjacent rows and formed with opposing in-turned hooks at their ends, the slats being slit where engaged with the links, portions of the slats margining the slits being removed from the general plane of the slats to enable the links to be received in the plane between the slats and the portions removed from the plane of the slats, the hook 25 openings being in the plane of the slat portions that are removed from the general plane of the slats whereby the spreading movement of the slats is limited and the slats are permitted to move closer together.

2. A metallic fabric including a plurality of slats placed side by side and formed of strip metal and rows of links each row be- 30

ing disposed between adjacent slats, the links being staggered in adjacent rows and formed with opposing in-turned hooks at their ends, the slats being slit where engaged with the links, portions of the slats margining the slits being removed from the general plane of the slats to enable the links to be received in the plane between the slats and the portions removed from the plane of the slats, the hook openings being in the plane of the slat portions that are removed from the general plane of the slats whereby the spreading movement of the slats is limited and the slats are permitted to move closer together. 40

3. A metallic fabric including a plurality of slats placed side by side and formed of strip metal and rows of links each disposed between adjacent slats, the links being staggered in adjacent rows and formed with opposing in-turned hooks at their ends, the slats being slit where engaged with the links, the portions of the slats margining each of the slits being relatively spread 45 apart vertically to form an opening in which the link there received may readily be transversely moved with respect to the engaging slat. 55

In witness whereof, I hereunto subscribe 60 my name this 26th day of October A. D., 1914.

HENRY F. HAGER.
